UNITED STATES PATENT OFFICE

149,778

DESIGN FOR A HOLDER FOR A SAFETY
RAZOR AND BLADES

Robert W. Schnell, Toledo, Ohio

Application October 28, 1946, Serial No. 134,347

Term of patent 7 years

(Cl. D4—3)

To all whom it may concern:

Be it known that I, Robert W. Schnell, a citizen of the United States and a resident of Toledo, Lucas County, Ohio, have invented a new, original, and ornamental Design for a Holder for a Safety Razor and Blades, of which the following is a specification, reference being had to the accompanying drawing, forming a part thereof.

In the drawing:

Figure 1 is a front perspective view of the holder for a safety razor and blades, showing my new design;

Figure 2 is a side elevation; and

Figure 3 is a top plan view of the holder for a safety razor and blades.

I claim:

The ornamental design for a holder for a safety razor and blades, as shown.

ROBERT W. SCHNELL.
